(57) **CLAIM**

The ornamental design for a cosmetic bottle and cap, substantially as shown.

DESCRIPTION

FIG. 1 is a top and front perspective view of a first embodiment of my new design for a cosmetic bottle and cap; FIG. 2 is a front elevational view of the cosmetic bottle and cap shown in FIG. 1;

FIG. 3 is a top plan view of the cosmetic bottle and cap shown in FIG. 1;

FIG. 4 is a rear elevational view of the cosmetic bottle and cap shown in FIG. 1;

FIG. 5 is a bottom plan view of the cosmetic bottle and cap shown in FIG. 1;

FIG. 6 is a right side elevational view of the cosmetic bottle and cap shown in FIG. 1;

FIG. 7 is a left side elevational view of the cosmetic bottle and cap shown in FIG. 1;

FIG. 8 is a top and front perspective view of a second embodiment of my new design for a cosmetic bottle and cap;

FIG. 9 is a front elevational view of the cosmetic bottle and cap shown in FIG. 8;

FIG. 10 is a top plan view of the cosmetic bottle and cap shown in FIG. 8;

FIG. 11 is rear elevational view of the cosmetic bottle and cap shown in FIG. 8;

FIG. 12 is a bottom plan view of the cosmetic bottle and cap shown in FIG. 8;

FIG. 13 is a right side elevational view of the cosmetic bottle and cap shown in FIG. 8; and,

FIG. 14 is a left side elevational view of the cosmetic bottle and cap shown in FIG. 8.
